UNITED STATES PATENT OFFICE.

WILLIAM HEIB, OF PHILADELPHIA, PENNSYLVANIA.

DESIGN FOR A GUTTER-HANGER SHANK.

SPECIFICATION forming part of Design No. 31,509, dated September 12, 1899.

Application filed August 21, 1899. Serial No. 728,019. Term of patent 7 years.

To all whom it may concern:

Be it known that I, WILLIAM HEIB, a citizen of the United States, residing at Philadelphia, in the county of Philadelphia and State of Pennsylvania, have invented and produced a new and original Design for Gutter-Hanger Shanks, of which the following is a specification, reference being had to the accompanying drawings, forming part thereof.

10 Figure 1 is a perspective view of a gutter-hanger shank, showing my new design. Fig. 2 is a side elevation, and Fig. 3 is a front elevation thereof.

As shown in the drawings, the leading or 15 material feature of my design consists of a channel-bar bent or twisted at the point A, so as to form two sections B and C in angular relation, having their planes and the planes of their respective flanges at right 20 angles to each other. The section B has its flanges *b* extending upward and tapering from

the bend A downward toward the opposite end of the section and is provided with holes *b'* through the web between the flanges. The section C has its flanges *c* extending substantially at right angles to the vertical plane of the channel or the plane of the web and is provided with the apertures *c'* through the web between the flanges. 25

Having described my invention, what I 30 claim as new, and desire to secure by Letters Patent, is—

The design for a gutter-hanger shank, substantially as shown and described.

In testimony whereof I have signed my 35 name to this specification in the presence of two subscribing witnesses.

WILLIAM HEIB.
